UNITED STATES PATENT OFFICE.

JAMES CLARKE HAGEY, OF CHICAGO, ILLINOIS, ASSIGNOR OF ONE-HALF TO THE CABLE COMPANY, OF CHICAGO, ILLINOIS, A CORPORATION OF ILLINOIS.

PRESSURE-REGULATOR.

1,225,619.

Specification of Letters Patent.

Patented May 8, 1917.

Application filed May 11, 1908. Serial No. 432,200.

To all whom it may concern:

Be it known that I, JAMES CLARKE HAGEY, a citizen of the United States, residing at Chicago, in the county of Cook and State of Illinois, have invented new and useful Improvements in Pressure-Regulators, of which the following is a specification.

My invention relates to automatic regulation of fluid pressure and one object there-
10 of is to provide a simple and efficient regu-
lating device.

Another object of my invention is to pro-
vide means through which the degree of au-
tomatic regulation may be instantly varied
15 either automatically or at will.

The invention is particularly applicable
to pneumatically operated devices for play-
ing musical instruments and includes in a
20 modified form one of the devices shown and
described in my application, Serial No.
280,304, filed Sept. 27, 1905.

Figure 1 is a partly sectional front view
showing my improved construction of the
pressure-controlling system of an automatic
25 musical instrument;

Fig. 2 is a similar view showing a modifi-
cation of my regulating device in connection
30 with a pressure-controlling system arranged
upon customary principles;

Fig. 3 is an enlarged view in vertical sec-
tion of the regulating device shown in Fig.
35 1; and

Fig. 4 is an enlarged view in vertical sec-
tion of the regulating device shown in Fig. 2.

I have shown and will describe the invention
35 in connection with an automatic play-
ing device for musical instruments operated
by wind pressure less than atmospheric pres-
sure, that is, suction, or as I prefer to term
40 it, wind-tension, but I do not wish to be lim-
ited to the use of the invention in connection
with this particular class of devices, as it
will be readily understood that slight con-
45 structive modifications will adapt it for use

in such automatic playing devices when op-
erated by wind-pressure greater than atmos-
pheric pressure and that the exact principles
and purposes may be retained when used in
50 connection with other fluids than air and
upon other mechanisms than those connected
with musical instruments.

Pneumatically-operated music-playing de-
vices are usually controlled by a moving
55 note-selective means, such as a perforated
sheet, and comprise at least two pneumatic

divisions wherein the wind-tension is under
separate regulation and control, as, for in-
stance, the note-sounding division and the
controller-propelling division.

I provide a regulating device which may 60
be advantageously used in connection with
either one of these divisions, furnishing un-
usually sensitive response to the spasmodic
demands of the pneumatics of the note-
sounding division when connected therewith 65
and unusually even regulation of the wind-
tension when connected with the controller-
propelling division.

A regulating bellows, or chamber, is usu-
ally employed for maintaining the lightest 70
desired wind-tension in the wind-ways lead-
ing to the pneumatics of the note-sounding
division for pianissimo effects and if this
wind-tension is to be varied to produce for-
tissimo effects such variation is accomplished 75
by operating a manually-controlled con-
stricting valve situated somewhere in the
said wind-ways to permit direct communica-
tion with a high-tension reservoir or the
pumping mechanism. I have found that the 80
most desirable regulator maintaining this
light tension is one possessing the minimum
reservoir capacity consistent with an efficient
regulation of ample valve-port area. A suffi-
ciently large valve-port should be opened or 85
closed simultaneously with the varying de-
mand from the pneumatics and such sim-
ultaneous action is not found in constructions
wherein the regulating chamber is of dimen-
sions large enough to constitute a substan- 90
tial reservoir. Difficulty has been expe-
rienced in combining a small enough regu-
lating chamber with a large enough valve-
port, as variation in the degree of wind-
tension supplied by the pumping mechanism 95
acts upon the face of the regulator-valve
exposed thereto and modifies the action of
the regulator.

In Figs. 2 and 4, I have illustrated that
part of my invention claimed by me to elimi- 100
nate this difficulty and this part of the device
is complete in itself in so far as concerns
absolute regulation of wind-tension at an
established degree.

Wind-tension is produced in the chamber 105
A by means of a suitable pumping mecha-
nism (not shown) and under normal condi-
tions may extend without limitation to the
pneumatics (not shown) of the note-sound-
ing division through open ports B and C 110

and the passage D. The regulating chamber E is also under tension extending from chamber A through passage F and port G. The movable member L of the regulating chamber automatically adjusts a valve over the port G by means of the valve-stem or link M and through such adjustment regulates the degree of tension in the regulating chamber at a point determined by the spring H. Connection of chamber E is made with the note-sounding pneumatics through port I and passages J and D. Adjustment of the constricting valve K varies the opening of port B and therefore the operation of the note-sounding pneumatics by the full power of wind-tension in chamber A, and complete closure of this port prevents the said operation except by the reduced degree of tension in the regulating chamber E.

I have indicated by the letter N, at the right hand end of Figs. 1 and 2, a duplication of the regulating device, shown in each figure at the opposite end thereof, comprising the chamber E and other component parts. N represents the chamber E arranged for control of the wind-tension for the controller-propelling division. Under certain conditions, the wind-tension in chamber A may extend without limitation to the propelling device (not shown) through the open port O and passage P (see Fig. 1), but normally this port is closed and the operation of the propelling device is limited to the reduced degree of tension in the regulating chamber N. The windways extending from chamber A through chamber N to port Q (Fig. 1) are arranged reversely to those shown in connection with chamber E, at the opposite end of Fig. 2, and the ports B and V are relatively similar to the ports O and Q, so that regulated tension may extend from the chamber N to the propelling device through port Q and passage P. Adjustment of the valve R varies the opening of port Q and therefore the operation of the propelling device.

Under certain conditions, it is desirable to render the note-sounding division inoperative and I have shown means for this purpose comprising valves S and T which may be drawn across the ports V and C respectively. It is the usual custom to connect these valves for simultaneous movement with the valve W (see Fig. 1) so that the ports V and C may be closed and the port O opened by a single movement and the arrangement reversed by reversal of the movement.

I have described the parts usually employed in devices of this class and their purposes and I shall now explain the construction and operation of my improvements.

1 (Figs. 3 and 4) is a pneumatic having a hinged movable member 2 and provided therein with an inlet 3. The pneumatic is secured to a rigid supporting arm 4 in such

position that the member 2 may act as a valve over the port G. The member 2 is provided upon its face with suitable packing to insure tight closure over the port and its operation may be accomplished in any desirable manner. I employ the usual valve-stem or link M for this purpose.

During operation, wind-tension in the chamber A may exhaust the regulating chamber E through the valve-controlled port G and move the member L under tension of the spring H. Such movement of the member L operates the member 2 of the pneumatic 1 by means of link M to vary the opening of port G. The spasmodic and variable admission of air through port I from the note-striking pneumatics causes a compensating adjustment of the member 2. When this member is held closed over the port G, the same degree of wind-tension acts upon the opposite sides of the said member through inlet 3. The port area covered by member 2 and the area of the said member exposed in the pneumatic 1 are directly proportionate and I find that, when the proportions of these areas are correctly established, delicate and positive regulation of wind-tension may be effected by a relatively small regulating chamber. The pneumatic 1 in this manner constitutes a practically constructed balanced valve.

The further development of my invention has to do with the elimination of a difficulty that has been experienced in the control of wind-tension in instruments employing the described constricting valve. The area of the port controlled by this valve bears a definite relation to the total cubic volume of the pneumatics to be simultaneously operated. Where one pneumatic is to be operated, the constricting valve must be set at a certain position, and, where a number are to be operated simultaneously, the valve must be moved to a new position in order to permit operation of the greater number with the same power. A constant readjustment of this valve is therefore necessary in order to produce, even approximately, the desired effect, and, since the demand from the pneumatics is constantly varying, it is almost impossible to properly manipulate this constricting valve. I purpose its elimination, therefore, and depend upon the automatic regulation of the valve controlled by the regulating chamber to compensate for the variation in the demand from the pneumatics.

In such an instance, I employ a quickly-gathering spring (H, Figs. 1 and 3) to provide tension in the regulating chamber E, that is, a spring which quickly increases in power as it is moved from inactive position. I extend the link or stem M far enough beyond the member L of the chamber E to afford attachment therewith of a device

mounted upon and movable with the said member. This device may be of a variety of constructions and may either be operated manually or pneumatically. It consists, 5 however, of a mechanism for adjusting the distance between the two members 2 and L. If the link M is pulled outwardly from the chamber E by the said mechanism then the member 2 must move nearer the member L 10 and consequently the said member L must expand the spring H to an increased degree in order to close the member 2 over the port G. Therefore, if the link M is varied in its position with relation to the member L the 15 tension of the spring H must also be varied and consequently the wind-tension in the chamber E.

To obtain a gradual variation in the wind-tension, it may be advisable to manually 20 adjust the controlling mechanism thus described and I have shown a means for such manual adjustment in Fig. 1, comprising link 5, crank 6, link 7, and controlling lever 8. In instances demanding quickly 25 accentuated effects, I prefer to employ a pneumatic as at 9 which is provided with tubes or nipples 17, expanded by the spring 11, and operatively connected with the link M by an arm extending beyond its hinged 30 end. Under this arrangement, collapse of the pneumatic draws the link outwardly from chamber E.

Pneumatic collapse or inflation of the pneumatic 9 may be accomplished by means 35 of a valve controlled in turn either by the controlling sheet or by a conveniently located finger-piston. I have considered it unnecessary to further complicate the drawings for the purpose of showing this valve 40 or the method of its control, as any particular form of valve for this purpose is not a part of this invention.

I have shown an adjustable nut upon the link 5 which will act against the lug or 45 screw-eye 10 when moved to adjust the movable member of the pneumatic 9 in a collapsing direction but will not interfere with the pneumatic collapse thereof at any point in this manually adjusted movement.

50 It will thus be seen that I provide a construction by which, when connected with the note-sounding division, the degree of tension for operating the pneumatics may be varied either at will, without experiencing the hereinbefore described difficulty in manipulation of a constricting valve, or by the controlling-sheet.

In the type of automatic music-playing 60 instruments employing a perforated controlling-sheet, the said sheet is drawn across a tracker having apertures therein for registration with the perforations in the sheet. The majority of these instruments are operated by varying degrees of wind-tension 65 and this tension is transmitted to the aper-

tures of the tracker by means well known to those conversant with the art. The sheet-propelling device should operate to give uniform movement at adjustable predetermined degrees of speed. A well recognized difficulty in obtaining this uniform movement is due to the fact that increase in the degree of wind-tension for variation in musical expression also increases the tension in the tracker-apertures and adds to the 70 friction of the sheet against the tracker. This amounts to a continual variation in the load upon the sheet-propelling device. It has been considered advisable to regulate the wind-tension for operation of the propelling device at an unvarying degree and to permit adjustment through a valve-controlled port located between the regulating device and the said propelling device. As the operating tension is unvarying and the 80 load is variable, it is obvious that variation must occur in the speed of the propelling device.

My improved regulating device, when used in connection with the controller propelling division, provides compensation for the described variation in load.

It will be seen, upon reference to Fig. 3, that the working length of each of the springs H and 11 may be adjusted by transfixing the springs with the pins 14 and 16 at any desired point and the movable members of the chamber E and pneumatic 9 may be adjusted in connection with the respective springs by means of the screw-nuts 12 100 and 13.

The device is first placed in position as shown at N in Fig. 1 but the tubes 15 are not connected therewith. The degree of wind-tension in chamber N is then determined for correct operation of the propelling device by adjustment of the nut 12 105 (Fig. 3). Such adjustment should be made with a fairly uniform tension in the chamber A, as, otherwise, the consequent variation in the load, hereinbefore described but not yet cared for, would modify the action of the propelling device.

The tubes 15 are then slipped over the nipples 17. These tubes lead from the interior of pneumatic 9 to any convenient point of attachment with such windways as may be under the same degrees of variable tension as the tracker-apertures. The tension in the windways, to which the tubes 15 115 are connected, is then reduced to the lightest degree desired for note-sounding purposes and the nut 13 is adjusted to apply only sufficient tension from the spring 11 to prevent a partial collapse of pneumatic 125 9 by this lightest desired degree of tension. Upon increase of tension in the windways mentioned to the maximum degree desired, a second adjustment of the tension of spring 11 is made by means of pin 16 to correct 130

the working length of the spring. The spring should be strong enough to prevent complete collapse of pneumatic 9 excepting by the most extreme degree of high tension in the note-sounding division. Such regulation by means of the pin is intended to vary the inherent gathering power of the spring and naturally affects the former adjustment by means of the nut 13. The said nut must then be readjusted to restore only sufficient tension of the spring upon the movable member of the pneumatic to prevent partial collapse thereof by the before-mentioned lightest desired degree of tension in the note-sounding division.

By this method of double-adjustment of the spring 11, the pneumatic will remain expanded under the said lightest desired degree of wind-tension and the degrees of its collapse will be proportionate with the increase of tension in the note-sounding division and the tracker-apertures.

Following the adjustment of spring 11, a corresponding adjustment may be made of the spring H to complete the compensating feature of my invention. The working length of this spring may be corrected by means of the pin 14. The spring should be strong enough to cause a sufficient degree of wind-tension in chamber N for the proper operation of the propelling mechanism during the presence of the maximum degree of tension in the tracker-apertures of the note-sounding division. The nut 12 will have to be re-adjusted to restore the correct tension to the spring H after disturbance thereof by the adjustment of pin 14. This may be easily done upon disconnection of the tubes 15. The varying degrees of wind-tension for musical expression in the note-sounding division acts, as hereinbefore stated, in the tracker-apertures and must extend thereto through passage D. I have therefore shown connection of the tubes 15, in Fig. 1, with a chamber in direct communication with this passage D.

The operation of my device, shown in Figs. 1, and 3, for regulation of wind-tension in connection with the controller-propelling division, is as follows: Wind-tension may be produced in chamber A at varying degrees according to the operation of the pumping mechanism, but my novel construction of the regulating valve controlling port G serves to maintain in chamber N a degree of tension unaffected by this variation. N (Fig. 1) is a duplication of chamber E. Variation in the tension in the passage D and consequently in the tracker-apertures, however, directly affects the tension in chamber N by means of tubes 15 and pneumatic 9. So long as the tension in passage D is the lightest desired, the spring 11 prevents even a partial collapse of pneumatic 9, but, upon an increase thereof, the

said pneumatic is proportionately collapsed and the movable member 2 is drawn nearer the member L of chamber N. The member L is instantly compelled to increase the expansion of spring H in order to maintain regulation of tension under this shifted relative position of the member 2. Increase in the degree of tension in the passage D therefore causes proportionate increase in the degree of tension in chamber N, which is the effect desired.

It will thus be seen that, when increased tension in the tracker-apertures causes an increase in the load for the propelling device, a simultaneous and compensating increase is effected in the power applied to operate the said device.

The principles of the invention herein described may be applied equally well in pressure regulators for gas, wherein an automatic increase in the degree of regulated pressure is desired to compensate for an increase in consumption, and the same principles may be employed in automatic water-heating devices, wherein the water-pressure at a given point may determine the regulation of the heat-producing fluid. Many other devices may be improved by the employment of my invention and I desire, therefore, not to be limited to its use in connection with the particular mechanisms herein shown and claimed.

I claim—

1. The combination, with a pressure chamber, a pressure-regulating chamber, a communication between said chambers, a valve controlling said communication and means for automatically operating said valve upon pressure-variation in said regulating chamber, of a perforation in said valve and means (1) operable through said perforation to act with counterbalancing effect upon said valve.

2. In combination with a pressure chamber, a pressure regulator comprising a chamber (E), a communication (G) between the pressure chamber and said chamber (E), a valve (2) positioned upon movement to close said communication, means (L) operating to move said valve upon pressure-variation in said chamber (E), means (1) to act with counterbalancing effect upon said valve and a perforation (3) in said valve through which the second named means communicates with the pressure chamber upon closure of said communication by said valve.

3. In a pressure regulator, the combination, with a pressure chamber, a passage for communication with said chamber and a valve acting upon variation in the degree of pressure in said chamber to control the communication of said passage, of a second chamber operatively connected to act with counterbalancing effect upon said valve dur-

ing control of the communication of said passage by said valve.

4. In a pressure regulator, the combination, with a pressure chamber, a passage for communication with said chamber and a valve acting upon variation in the degree of pressure in said chamber to control the communication of said passage, of a perforation in said valve and an auxiliary chamber in communication with said perforation.

5. In combination with a pressure chamber, a pressure regulator comprising a chamber (E), a communication (G) between the pressure chamber and said chamber (E), a valve (2) positioned upon movement to control said communication, said valve offering one of its faces to the pressure in the pressure chamber, a second chamber (1) operatively connected with said valve and an opening (3) in said valve through which the pressure in the pressure chamber may act in said second chamber with counterbalancing effect upon said valve.

6. The combination of a regulating pneumatic having a vibratory leaf or member, a passage communicating with the interior of said pneumatic, and a second pneumatic arranged within said regulating pneumatic, said second pneumatic having a swinging or vibratory leaf or member connected with the vibratory member of said regulating pneumatic, said swinging leaf of said inner pneumatic providing a valve for said passage and being movable by said vibratory member of the regulating pneumatic independently of the other leaf or member of said inner pneumatic.

7. The combination with a main pneumatic provided with a port or passage to be regulated, a small or supplemental pneumatic arranged within said main pneumatic and forming a valve for said port, and means whereby said supplemental pneumatic is opened and closed so as to control said port by the movement of the vibratory member of said main pneumatic.

8. The combination with a main pneumatic provided with a port or passage to be regulated, a small or supplemental pneumatic arranged within said main pneumatic and forming a valve for said port, and mechanical connection with the vibratory member of the supplemental pneumatic for actuating said member independent of the other member by the movement of the vibratory member of the main pneumatic.

9. The combination with a main pneumatic having a port or passage to be regulated, a supplemental pneumatic confined within said main pneumatic and mounted rigidly therein, the swinging or vibratory leaf of said supplemental pneumatic providing a valve for said port, and a connection from said vibratory member of said supplemental pneumatic to the vibratory

member of the main pneumatic, whereby the movement of the latter operates said movable member of the supplemental pneumatic to control said port.

10. The combination of a main pneumatic having a port to be regulated, a supplemental pneumatic arranged within said main pneumatic and rigidly mounted therein, said supplemental pneumatic having its swinging member mounted to control said port, and a rod connected with the swinging member of said supplemental pneumatic and also connected with the movable member of the main pneumatic, whereby the movement of the latter actuates the former to control said port. 70 75 80

11. The combination of a main pneumatic having a port to be regulated, a supplemental pneumatic arranged within said main pneumatic and rigidly mounted therein, said supplemental pneumatic having its swinging member mounted to control said port, a rod connected with the swinging member of said supplemental pneumatic and also connected with the movable member of the main pneumatic, whereby the movement of the latter actuates the former to control said port. 85 90 95

12. The combination of a main pneumatic having a port to be regulated, a supplemental pneumatic arranged within said main pneumatic and rigidly mounted therein, said supplemental pneumatic having its swinging member mounted to control said port, a rod connected with the swinging member of said supplemental pneumatic and also connected with the movable member of the main pneumatic, whereby the movement of the latter actuates the former to control said port, a third pneumatic mounted upon the vibratory member of the main pneumatic and connected with said rod 100 105 110

13. The combination of a main pneumatic having a port to be regulated, a supplemental pneumatic arranged within said main pneumatic and rigidly mounted therein, said supplemental pneumatic having its swinging member mounted to control said port, a rod connected with the swinging member of said supplemental pneumatic and also connected with the movable member of the main pneumatic, whereby the movement of the latter actuates the former to control said port, a third pneumatic mounted upon the vibratory member of the main pneumatic and connected with said rod 115 120 125 130

is connected with the swinging member of the supplemental pneumatic, tension springs controlling the swinging member of the main pneumatic and also controlling said third mentioned pneumatic, and means whereby said springs may be adjusted in length to vary their tension.

14. The combination of a main pneumatic having a port to be regulated, a supplemental pneumatic arranged within said main pneumatic and rigidly mounted therein, said supplemental pneumatic having its swinging member mounted to control said port, a rod connected with the swinging member of said supplemental pneumatic and also connected with the movable member of the main pneumatic, whereby the movement of the latter actuates the former to control said port, a third pneumatic mounted upon the vibratory member of the main pneumatic and connected with said rod which is connected with the swinging member of the supplemental pneumatic, tension springs controlling the swinging member of the main pneumatic and also controlling said third mentioned pneumatic, and means for controlling the pneumatic pressure within said third pneumatic independently of the pressure in the other pneumatics.

15. The combination of a main pneumatic having a port to be regulated, a supplemental pneumatic arranged within said main pneumatic and rigidly mounted therein, said supplemental pneumatic having its swinging member mounted to control said port, a rod connected with the swinging member of said supplemental pneumatic and also connected with the movable member of the main pneumatic, whereby the movement of the latter actuates the former to control said port, a third pneumatic mounted upon the vibratory member of the main pneumatic and connected with said rod which is connected with the swinging member of the supplemental pneumatic, tension springs controlling the swinging member of the main pneumatic and also controlling said third mentioned pneumatic, and means whereby the spring for said third pneumatic may be independently adjusted.

16. The combination of a main pneumatic having a port to be regulated, a supplemental pneumatic arranged within said main pneumatic and rigidly mounted therein, said supplemental pneumatic having its swinging member mounted to control said port, a rod connected with the swinging member of said supplemental pneumatic and also connected with the movable member of the main pneumatic, whereby the movement of the latter actuates the former to control said port, a third pneumatic mounted upon the vibratory member of the main pneumatic and connected with said rod which is connected with the swinging member of

the supplemental pneumatic, tension springs controlling the swinging member of the main pneumatic and also controlling said third mentioned pneumatic, and means whereby the spring for said third pneumatic may be independently adjusted, said means comprising a manually operable lever and connections between the same and said spring.

17. The combination with first and second fluid pressure systems, of a pressure regulator operated by and acting upon the pressure in the first of said systems, and means through which varying changes in pressure in the second of said systems may determine the pressure which said regulator automatically acts to maintain in the first of said systems.

18. The combination with first and second fluid pressure systems, of a member movable by the pressure in the first of said systems into various positions between the extremes of its movement, the various positions of said member being indicative of various pressures in the first of said systems, a pressure regulator operated by and acting upon the pressure in the second of said systems, and means through which the position of said member may determine the pressure to be maintained by said regulator in the second of said systems.

19. The combination with first and second fluid pressure systems and a pressure regulator operated by and acting upon the pressure in the first of said systems, of means movable by pressure into varying positions through which varying changes in pressure in the second of said systems may adjust the automatic action of said regulator.

20. The combination with first and second fluid pressure systems and a pressure regulator operated by and acting upon the pressure in the first of said systems, of means for automatically applying varying changes in pressure which occur in the second of said systems to produce effects upon the action of said regulator and thereby determine the regulation of pressure to be provided by said regulator in the first of said systems.

21. The combination with first and second fluid pressure systems and a pressure regulator operated by and acting upon the pressure in the first of said systems, of a member movable by the pressure in the second of said systems into various positions between the extremes of its movement and acting to variably position an adjustable part of said regulator, the various positions of said member being indicative of various pressures in the second of said systems.

22. The combination with a plurality of fluid pressure systems and a pressure regulator operated by and acting upon the pressure in one of said systems, of a pressure chamber connected with another of

said systems and having a movable member, and means through which varying movements of the movable member of said chamber may cause varying changes in the regulation of pressure by said regulator in said one of said systems.

23. The combination with first and second fluid pressure systems and a pressure regulator operated by and acting upon the pressure in the first of said systems, of a pressure chamber connected with the second of said systems and having a member movable by the pressure in said chamber into various positions between the extremes of its movement, the various positions of said member being indicative of various pressures in the second of said systems, and means through which varying movements of the member of said chamber may cause varying changes in the regulated pressure provided by said regulator in the first of said systems.

24. The combination with first and second fluid pressure systems and a pressure regulator operated by and acting upon the pressure in the first of said systems, of a movable member and means through which varying movements of said member may cause varying changes in the regulated pressure provided by said regulator in the first of said systems, variable movements of said member being caused by and corresponding with changes in pressure in the second of said systems.

25. The combination with a plurality of fluid pressure systems and a pressure regulator operated by and acting upon the pressure in one of said systems, of a pressure chamber connected with another of said systems and having a movable member, and means through which varying movements of said member may cause varying changes in the regulation of pressure by said regulator in said one of said systems, variable movements of said member being caused by and corresponding with changes in pressure in said chamber.

26. The combination with first and second fluid pressure systems and a pressure regulator operated by and acting upon the pressure in the first of said systems, of a pressure chamber connected with the second of said systems and having a member movable by the pressure in said chamber into various positions between the extremes of its movement, the various positions of said member being indicative of various pressures in said chamber, and means through which the position of said member may determine the regulation of pressure to be provided by said regulator in the first of said systems.

27. The combination with first and second fluid pressure systems and a pressure regulator operated by and acting upon the

pressure in the first of said systems, of a pressure chamber connected with the second of said systems and having a member movable by the pressure in said chamber into various positions between the extremes of its movement, the various positions of said member being indicative of various pressures in said chamber, and means through which the position of said member may determine the effective power of said regulator in regulating the pressure in the first of said systems.

28. The combination with first and second fluid pressure systems and a pressure regulator regulating the pressure in the first of said systems, of a pressure chamber connected with the second of said systems and having a movable member, variable movements of said member being caused by and corresponding with changes in pressure in said chamber, and means through which varying movements of said member may cause varying adjustments in the automatic action of said regulator.

29. The combination with first and second fluid pressure systems and a pressure regulator regulating the pressure in the first of said systems, of a pressure chamber connected with the second of said systems and having a movable member acting to move an adjustable part of said regulator, variable movements of said member being caused by and corresponding with changes in pressure in said chamber.

30. The combination with first and second fluid pressure systems and a pressure regulator regulating the pressure in the first of said systems, of a pressure chamber connected with the second of said systems and having a member movable by the pressure in said chamber into various positions between the extremes of its movement, the various positions of said member being indicative of various pressures in said chamber, and means through which the position of said member may determine an adjustment of said regulator.

31. The combination with first and second fluid pressure systems and a pressure regulator regulating the pressure in the first of said systems, of a pressure chamber connected with the second of said systems and having a member movable by the pressure in said chamber into various positions between the extremes of its movement and acting to position an adjustable part of said regulator, the various positions of said member being indicative of various pressures in said chamber.

32. The combination with a motor for advancing a music sheet across a tracker, of means for automatically varying the motor operating pressure in accordance with and controlled by variations in the retarding influence of said tracker upon said sheet.

33. The combination with a motor for advancing the music sheet of an automatic musical instrument, of means for automatically controlling the motor operating pressure by variations in the action operating pressure.

34. The combination with a pressure regulator having a movable member and regulating valve, of a pressure chamber positioned upon the outer side of and movable with said member, and acting upon said valve.

35. The combination with a pressure regulator having a pressure chamber, a movable member, and a regulating valve, of a second pressure chamber subject to pressure independent of the pressure within the first said chamber and having a member movable by the pressure within said second chamber into various positions between the extremes of its movement, the second said member co-operating with the first said member in the operation of said valve, and means for producing various degrees of pressure within said second chamber to cause the positioning of the second said member in said various positions, each position thereof being in accordance with the degree of pressure within said second chamber.

36. The combination with a pressure regulator having a movable member and a regulating valve, of a pressure chamber movable with said member and having a movable member movable by the pressure within said chamber into various positions between the extremes of its movement and acting to move said valve, and means for producing various degrees of pressure within said chamber to cause the movement of the second said member into said various positions, such movement being proportionate to the changes in the degree of pressure within said chamber.

37. The combination with a pressure regulator having a movable member and a regulating valve, of a second movable member carried by said movable member, a pressure chamber acting to move said valve by means of said second movable member, said second member being movable by the pressure within said chamber into various positions between the extremes of its movement, and means for producing various pressures with-

in said chamber to cause the positioning of said second movable member in said various positions, said various positions being in accordance with said various pressures.

38. The combination with a pressure regulator having a movable member and a regulating valve, of a pressure chamber movable with said member and having a second movable member movable by the pressure within said chamber into various positions between the extremes of its movement and acting through decrease of pressure within said chamber to move said valve in one direction, a spring acting to oppose the movement of said second movable member in said one direction, and means for decreasing the pressure within said chamber in various degrees to cause the positioning of said second movable member in said various positions, each position thereof being in accordance with the degree to which the pressure within said chamber has been decreased.

39. The combination of a pressure regulator having a movable member and a regulating valve, and a pressure chamber having a movable member movable by the pressure within said chamber into various positions between the extremes of its movement and acting through decrease of pressure within said chamber to move said valve, a spring alone determining the operative pressure within said pressure chamber, and means for decreasing the pressure within said chamber in various degrees to act in opposition to the action of said spring in positioning the movable member of said chamber in said various positions.

40. The combination with a pressure regulator having a pressure controlled movable member and a pressure controlling valve operated thereby, of a pressure chamber positioned without said regulator, upon the movable member thereof and operatively connected with the valve operated thereby.

Signed at Chicago, Illinois, this eighth day of May, 1908, in the presence of two 100 subscribing witnesses.

JAMES CLARKE HAGEY.
